(57) **CLAIM**

The ornamental design for a bottle cap collar, as shown and described.

DESCRIPTION

FIG. 1 is a top perspective view of a bottle cap collar, shown in a position of use with an exemplary bottle; FIG. 2 is another perspective view of the bottle cap collar thereof, shown independent of the exemplary bottle to show aspects of the design not visible when combined; FIG. 3 is a front elevational view of the bottle cap collar thereof; FIG. 4 is a rear elevational view of the bottle cap collar thereof; FIG. 5 is a left side elevational view of the bottle cap collar thereof; FIG. 6 is a right side elevational view of the bottle cap collar thereof; FIG. 7 is a top plan view of the bottle cap collar; and, FIG. 8 is a bottom plan view of the bottle cap collar thereof. The broken lines are shown for the purpose of illustrating environmental subject matter of an exemplary bottle and form no part of the claimed design.
